UNITED STATES PATENT OFFICE.

SAMUEL C. TOWNSEND, OF BALTIMORE, MARYLAND.

DESIGN FOR A HAT.

SPECIFICATION forming part of Design No. 29,099, dated July 26, 1898.

Application filed March 17, 1898. Serial No. 674,267. Term of patent 3½ years.

To all whom it may concern:

Be it known that I, SAMUEL C. TOWNSEND, citizen of the United States, residing in the city of Baltimore, in the State of Maryland, have invented and produced a new and original Design for Hats, of which the following is specification, reference being had to the accompanying drawings, forming part thereof.

Figure 1 is a perspective view of a hat, showing my new design. Fig. 2 is a side elevation, lightly perspective, of the same.

As shown in the drawings, the leading and material feature of my design consists of a hat, the top of the crown of which is made of braids of coarse straw, plaited with roughened surfaces in which the braid which forms the edge of the top of the crown A extends to the extreme edge of the crown all round and to a

plane coincident with the vertical wall of the crown B. The side of the crown is vertical and substantially at right angles to the top and to the braid a, which projects to the upper edge of the side wall of the crown, all disposed and arranged as shown in Figs. 1 and 2.

Having described my invention, what I claim as new, and desire to secure by Letters Patent, is—

The design for a hat, as herein shown and described.

Signed by me at Baltimore city, State of Maryland, this 16th day of March, 1898.

SAMUEL C. TOWNSEND.
